(57) CLAIM

The ornamental design for a phone and writing instrument holder, as shown and described.

DESCRIPTION

FIG. 1 is a perspective view of a phone and writing instrument holder showing our new design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top plan view of FIG. 1; and,

FIG. 7 is a bottom plan view of FIG. 1.

The portions in broken lines in FIGS. 1-7 are included for the purpose of showing features that form no part of the claimed design.

1 Claim, 7 Drawing Sheets
